UNITED STATES PATENT OFFICE

2,529,056

LINE ADJUSTER

Paul P. Sprowl, Bakersfield, Calif.

Application June 16, 1947, Serial No. 754,937

1 Claim. (Cl. 33—86)

1

This invention relates to a line adjuster, and more particularly, has reference to a means, embodied in the construction of a device of this type, whereby a brick layer's line may be retained in position to permit laying of bricks, blocks, or the like, in a straight line.

The primary object of the invention is to provide a device of the character described which is adapted to retain the line in the desired position tightly, conveniently, and in the predetermined position desired.

A further important object of the invention is to provide a device of the type stated which is adapted to engage the line in any of various adjusted positions, whereby to lengthen the line, tighten it, or make such other adjustments as may be necessary.

Still another important object of the invention is to provide a device of the character described which, with the cooperation of the line, is adapted to grip a corner brick or block tightly, and to remain in said engagement with the object gripped without further attention, whereby the brick layer can proceed to lay the bricks or blocks with ease.

Still another important object of the invention is to provide means, in a device of the type stated, whereby a single line may be drawn taut in adjusted position on two sides of a building, permitting the laying of bricks simultaneously, and without difficulty, along both sides.

Still another object is to provide a device of this type which can be constructed with a minimum of expense, is easily mounted in position, extremely durable, and capable of ready and speedy adjustment.

With the foregoing and other objects in view which will appear as the description proceeds, the invention consists of certain novel details of construction and combinations of parts, herein-after more fully described and pointed out in the claims, it being understood that changes may be made in the construction and arrangement of parts, without departing from the spirit of the invention as claimed.

Referring to the drawing

Figure 1 is a plan view, somewhat diagrammatic, showing the device in mounted position, ready for the laying of the bricks or blocks.

Figure 2 is a plan view, showing the device as it appears when engaging the end of a line carried thereby.

Figure 3 is an elevational view, taken from the right of Figure 2.

Figure 4 is a plan view, somewhat diagrammatic, showing the invention as applied to permit laying of bricks along two sides of a building.

Figure 5 is a plan view of a modification, adapted particularly to serve as an intermediate member when the invention is applied for laying bricks along two sides of a building.

Figure 6 is an elevational view taken from the right of Figure 5.

2

Figure 7 is a side elevational view of a modified form.

Figure 8 is a plan view of a fourth modification of the invention.

Referring to the drawing in detail, 5 and 6 designate respective sides of the embodiment of the invention illustrated in Figures 2 and 3, these sides being readily formed from rectangular blocks of any desired material, such as wood or the like, and being suitably joined at one end in perpendicular relation to each other, whereby the respective inner surfaces 7 and 8 thereof may be fully perpendicular.

In the embodiment illustrated, transverse angular teeth 9 are provided on the inner surface 7 of side 5, these being adapted to grip tightly the outer surface of a brick "A," whereby the device may be effectively retained in properly mounted position on the brick or block. In this connection, although I have shown such teeth as being formed in only one of the two inner surfaces 7 and 8, it is obviously within the spirit of the invention, to an extent not believed to require separate illustration, that similar teeth 9 can be formed in the other inner surface 8, if desired.

Extended transversely through the side 5, and positioned preferably intermediate the upper and lower edges thereof, is an opening 10, the axis of which is parallel to, and closely spaced from, the plane in which lies the inner surface 8 of side 6. This receives a line 11, and as clearly shown in Figure 2, the formation of opening 10 at the point stated results in line 11 lying closely against the inner surface 8, so that when the device is mounted against a corner block "A," line 11 will be pressingly retained between the surfaces of the block and the inner surface 8 of side 6.

Extended transversely through the side 6, adjacent its end, is a threaded opening 12, which communicates at its inner end with the opening 10, and which is in substantially perpendicular relation to said opening, as clearly shown in Figure 2. A thumb screw 13 is threadable in opening 12, and the inner end of the thumb screw may be tightened against the line 11 passed through opening 10, whereby to tightly retain the line 11 in fixed position.

One or more transverse openings 14 may be formed in either or both of the sides 5 and 6, for the purpose of receiving nails or the like, should it be desired to mount the device fixedly upon a batter board or the like.

Referring now to Figure 1, it is seen that by the provision of a device formed as described, two of these devices are adapted to cooperate in retaining in taut position a line 11. Each adjuster is positioned against the corner of a block "A," line 11 being stretched therebetween, with the ends of the line threaded through the opposed openings 10 of the separate devices. Line 11 is then drawn taut, in the desired position, and the thumb screws 13 of the devices are tightened against the ends thereof. The taut-

ness of the line 11, in cooperation with the teeth 7 of each device, causes the devices to be tightly retained in the position desired, and the line of blocks extending between the corner blocks "A" can be laid, with the exact proper position of each block being determined by aligning its outer face against the line 11.

It may be noted in this connection that the line 11 may be positioned in fully parallel relation to the lines of blocks to be laid, since the upper edges of the adjusters can be positioned flush with the upper edges of the blocks "A." Additionally, it is believed obvious that levels of any well known type, such as spirit levels or the like, can be embodied in each device, so that the device will be fully horizontal when mounted.

Should it be desired to secure the devices to batter boards or the like, nails can be driven through the openings 14 and into the batter boards for this purpose.

In the invention, it is possible for a single line to be stretched taut in proper position along two sides of the building. This is achieved by use of a modified form of the device, in cooperation with the forms previously described. Such a modified form is shown in Figure 5, and Figure 6. This comprises perpendicular sides 15 and 16, each of which is provided with openings corresponding to the opening 10, these openings being respectively designated at 17 and 18. Intermediate its ends, line 11 is threaded through these openings, and passed around the outer corner of the device, as shown at 19. In the side 15, a threaded opening 20, receiving thumb screw 21, communicates with opening 17, while in the side 16, threaded opening 22 containing thumb screw 23 communicates with the opening 18.

The use of this modified form of device is illustrated in Figure 4. As shown, the line, by the provision thereof, is drawn taut along two sides of the building, devices formed according to the first embodiment of the invention being mounted against corner blocks "B" and "D," while the modified form is mounted against intermediate corner block "C." The thumb screws of all the devices are tightened after proper adjustment has been determined, and the line 11 is thus retained taut in its adjusted position.

Another modified form is illustrated in Figure 7. This comprises perpendicularly disposed sides 24 and 25, formed and arranged as in the embodiment illustrated in Figure 2, that is, with a line-receiving opening corresponding to the opening 10, and a thumb screw corresponding to the thumb screw 13. An opening 26 is formed in side 24, parallel to and adjacent the thumb screw opening. Line 11, after having been threaded through opening corresponding to opening 10, is threaded outwardly through opening 26, and then inwardly through any of openings 27, 28, or 29. When the device is properly mounted in predetermined position on the corner brick, the openings 27, 28, or 29, can be selectively used to permit line 11 when stretched taut between two of the devices, to serve as a gauge, whereby a desired thickness of mortar, plus a brick, will meet line 11. Thus, one of these openings can be used as a gauge where three-eighths inch of mortar is desired, another for one-half inch, and another for one-quarter inch.

Referring to Figure 8, I have there shown a form of the device adapted for mounting on bricks having rounded corners. In this form, the perpendicular inner surfaces 30 and 31 meet the ends of a curvingly formed corner inner surface 75

32, which is adapted to engage the rounded corner of the brick. Nails 33, or teeth, may be used for the purpose of providing a gripping means.

It will be observed from the construction illustrated and described that my device is capable of providing a means which is readily adjustable, for the purpose of providing a fully level line whereby a course of bricks can be laid easily, with a proper level being maintained. Additionally, it is to be noted that by use of the device, it is possible to gauge the thickness of the mortar underlying the course of bricks to be laid, and it is additionally possible to so employ the invention as to stretch a line around two sides of a building, to permit separate courses of bricks to be laid along both sides simultaneously.

It may be further noted that within the spirit of the invention as claimed, the invention is obviously capable of being employed in connection with squaring lots, foundations, or the like.

Considering the form of the invention as seen in Fig. 5, it may be noted that the openings 17, 18 are respectively parallel to the inner faces of the opposite blocks 16 and 15. At the same time, one edge of the opening 17 is in the plane of the inner face of the block 16, while one edge of the opening 18 is in the plane of the inner face of the block 15. As a result of this construction, a cord can be extended through either one of the openings when the device is to be used as an end cord holder, or the cord can be extended as illustrated in Fig. 5 when the device is to be used as a corner cord holder. The cord is of substantially reduced width relative to the width of the respective openings as readily seen from Fig. 5. By reason of this arrangement the cord portions, when the device is used at the corner of a structure, are at right angles to each other, and extend almost into contact with each other while yet barely clearing. The cords are thus formed into right angled portions without possibility of bunching, or becoming entangled.

What is claimed is:

A line adjuster comprising a pair of flat blocks having plane inner faces intersecting at right angles, each block having an opening formed therein in intermediate its top and bottom edges and opening at its opposite ends upon said inner face and the outer face of the block, each opening being in parallelism with the inner face of the other block and one side edge of each opening being co-planar with said inner face of the other block; a cord extendable through said openings and of substantially less width than the width of each opening; and clamping screws threaded in the respective blocks, said screws projecting above the top edges of the blocks and extending downwardly from said top edges into communication with the respective openings.
